UNITED STATES PATENT OFFICE

MORRIS A. WEITZMAN, OF CHICAGO, ILLINOIS

HAT CLEANING MACHINE

Application filed September 29, 1930. Serial No. 484,977.

This invention relates in general to a hat cleaning machine and more particularly to a method and apparatus for cleaning and ironing hats.

5 An important object of the invention is to provide a method of cleaning hats of materials such as felt and the like in which the cleaning fluid is mechanically extracted from the hat after cleaning or extracted by centrifugal force so that much less time will be required for drying the hats and so that the cleaning fluid will not be wasted and may be used repeatedly and will not evaporate to permeate the surrounding atmosphere to the extent that fires or explosions may take place or that the air would be disagreeable for an operator to breathe.

20 Another important object is to provide mechanism for accomplishing the above mentioned result and for accomplishing that result efficiently and economically.

25 Another important object of the invention is to provide a novel, mechanically simple and efficient mechanical ironing device or apparatus for ironing hats and the like.

30 Another important object is to provide a simple and efficient hat holding spindle for hat cleaning machines and the like and such a device which may be used for holding hats through crown blocks or stretchers and the like.

35 Another important object is to provide a simple machine embodying all of the above mentioned features which may be produced and distributed at a low cost.

40 Numerous other objects and advantages of the invention will be apparent as it is better understood from the following description, which, taken in connection with the accompanying drawings, discloses a preferred embodiment thereof.

45 Referring to the drawings:

Figure 1 is a longitudinal vertical sectional view of a machine embodying my invention.

50 Fig. 2 is a plan view of the machine shown in Fig. 1.

55 Fig. 3 is an enlarged detail view of one of the hat holding spindles with portions broken away to show details of construction.

Fig. 4 is a plan view of the spindle shown in Fig. 3 having a hat stretcher attached thereto.

Fig. 5 is a section taken substantially on line 5—5 in Fig. 4 and illustrating the connection.

Fig. 6 is an enlarged detail view of the iron controlling and supporting devices shown in Fig. 1 with parts broken away to show details of construction.

Fig. 7 is a horizontal section taken substantially on line 7—7 in Fig. 6 and illustrating the yielding and reciprocating connection.

Fig. 8 is an end elevational view of the devices shown in Fig. 6 or viewing Fig. 6 from the right and clearly showing the plate support and brackets.

Fig. 9 is an elevational view of a brim block and illustrating the action of the plate and iron extension in ironing a curled brim, and

Fig. 10 is an enlarged view of a preferred form of the iron extension device or tool.

To illustrate the invention I have shown a frame 11, hat spindles 12 and 13, a tank or inclosure 14, an ironing mechanism 15 and a power means or motor 16.

While the frame 11 may be cast of metal or constructed of wood or the like, for simplicity I have shown a frame built up of standard pipe and fittings. The ordinary essentials of the frame 11 are standards or uprights 17 for supporting a benchlike top 18 and a tank supporting plate 19, and cross connectors or braces 20, 21 and 22. The pipes are or may be connected as indicated by means of pipe T 80 fittings 23 and pipe flanges 24 may be provided for the ends of the pipes and for connection to the top 18 and plate 19.

85 It is an object of the invention to extract the cleaning liquid from the hats mechanically and preferably by centrifugal force and to accomplish this the spindle 12 is arranged to spin the hat until the liquid is thrown off. To conserve the liquid for further use the spindle 12 is arranged in the inclosure 14. The spindle 12 preferably includes a central shaft 25 rotatably mounted in a bearing bracket 26 and provided with a fixed antifriction thrust collar 27. Companion antifriction bearing 90 collars or rings 28 and 29 are mounted in the 100

bracket 26 and in a cap 30 respectively. The cap 30 is preferably threadedly connected with the bracket 26 for securing the shaft in operative position as shown. The upper end 5 of the shaft 25 is drilled to provide a socket 31 for receiving a hat holding spindle 32, (Figs. 1 and 3) and the lower end of the shaft 25 is provided with an enlarged head 33, a friction pan 34 preferably having a 10 curved friction face 35 and a hub 36, bored to fit the shaft 25 and the enlarged head 33 as indicated, is mounted over the shaft and head and through keys 37 working in slots 38 relative axial movement of the pan 34 is permitted and a driving connection is effected. A spring 39 extending between the plate 19 and an antifriction bearing collar 40 normally holds the pan 34 against the enlarged head 33 as shown, (Fig. 1). The bearing 26 20 is rigidly secured to the frame through the plate 19 by means of rivets 41 or the like.

The inclosure 14 is preferably a sheet metal tank 42, and cover 43. The tank 42 is or may be substantially cylindrical and is provided with a curled flange 44 at its upper end and with a suitable sealed bottom 45. The bottom 45 is formed to provide a supporting rim 57 and an upwardly tapered flash portion 47 in which the cap 30 is tightly pressed. 30 A drain tube 48 is or may be provided and secured to the bottom or as indicated through which the cleaning liquid may be removed from the tank 42 after settling and for further use and a plug 49 may be provided for 35 closing the tube 48.

The cover 43 is preferably reversible as shown (Figs. 1 and 2) and formed of a flanged cover plate 51 having a curled edge 52 and provided with a suitable handle 53. An annular band 54 is secured in the flanged cover and to extend from the curled edge 52 thereof to form a depending locating flange for engaging in the tank 42 when the cover 43 is reversed. The band 54 also forms the side 45 walls of a receptacle 55 in which hats may be brushed with cleaning liquid or cleaned. An opening or drain tube 56 is provided through which the cleaning liquid is drained into the tank 42. A partition 57 is arranged 50 to extend across and divide the receptacle 55 to provide a well 58 in which a quantity of cleaning liquid may be stored for immediate use.

Power is transmitted to the spindle 12 from 55 the motor 16 through a shaft 60 extending from the motor and past the pan 34 and a friction wheel 61 formed on a hub 62 which is longitudinally shiftable along a squared or non-circular portion 63 of the shaft 60. 60 The position of the wheel 61 is adjustable through a control handle 64 having a bifurcated end 65 engaging the hub 62. The squared end of the shaft 60 is supported in bushings 66 rotatably mounted in the braces 65 22.

The spindle 13 may be any suitable shaft or the like upon which a hat block and hat may be mounted or secured and in the present embodiment includes a shaft 67 rotatably mounted in an end thrust bearing 68 and in 70 a bearing plate 69 secured to the top 18 by means of bolts 70 or the like. The top or free end 71 of the shaft 67 is preferably tapered or formed to support and rotate a hat holding spindle 72 or the like, or to support 75 a hat block direct.

The shaft 67 may be rotated from the motor 16 in any suitable manner and in the present instance I provide a belt drive including a pulley 73 suitably secured to the 80 shaft 67, a similar and smaller pulley 74 suitably secured to the shaft 60 and a belt 75 arranged about the pulleys 73 and 74 and over one or more idler pulleys 76 which may be carried by a bracket or link 77 pivoted on 85 a support 78. A spring 79 through the link 77 provides a means for taking up slack in the belt 75.

The hat holding spindle 72 may be any suitable extension shaft or the like upon 90 which a hat block indicated by lines 80 and 81, (Fig. 1) may be mounted. The lines 80 and 81 indicate the long and short diameters respectively of a hat crown block.

The preferred form of the spindles 72 and 95 32 is a central shaft 82, (Figs. 1, 3 4 and 5) formed to provide a threaded extension 83 of reduced diameter. A disc or plate 84 is mounted over the threaded extension and secured to the shaft 82 by means of a nut 100 85 engaging the threaded extension 83. A chuck member 86 adapted to engage in a bore 87 in a hat block 88 is drilled and tapped to engage the threaded extension 83. Similarly the threaded extension may be threaded 105 into an adjusting member 89 of a hat holder or stretcher 90 to clamp parts 91 and 92 thereof against the plate 84 for holding a hat mounted on the stretcher.

The lower end of the spindles 32 and 72 110 are formed in accordance with the spindles 12 and 13. The spindle 32 in the present instance is formed to fit in the socket 31 and drilled to receive a latch pin 93 mounted in a carrier 94 which is secured to the shaft 25. The spindle 72 is provided with a chuck collar 95 having a tapered seat therein for receiving the end 71 of the shaft 67, the drive being effected through friction. For dusting, brushing, 120 or the like a hat block may be chucked directly on the end 71 of the shaft 67 and a brim support or block 96, (Fig. 9) which will be later described may be substituted for the spindle 72.

To provide mechanism for pressing or ironing hats, an iron or ironing plate 101 is mounted adjacent the shaft 67 and provided with support and control apparatus for shifting or moving the plate 101 about a hat 130

block carried by the spindle 72 or on the block 96. This apparatus in the present embodiment includes a pivoted or hinged bracket 102 formed of spaced links 103 secured together by spacers 104 and 105 and pivotally connected to depending arms 106 formed on the bracket 69 through suitable shoulder bolts 107, a link or connecting bracket 108 hingedly connected to the ends of the links 103 of the bracket 102 and to the plate 101 through a suitable casting 109 suitably secured to the plate 101, and mechanism for actuating the plate through said devices.

The link 108 is or may be formed of sheet metal and to provide spaced and substantially parallel bars 111 connected together through a top plate 112 which may be extended to provide a handle 113 for manipulating the plate manually. At one end the bars 111 are hingedly connected to the ends of the links 103 through a bolt 114 and at the other end these bars are similarly connected to the bracket 109 through a suitable bolt 115. A tension spring 116 normally holds the link 108 against a stop provided by an adjustable plate 117 which is secured to the links 103 by means of screws 118 or the like. Similar tension springs 119 engaging pins 120 on the casting 109 and pins 121 carried by the bars 111 normally urge the plate in a clockwise direction. (Viewing Fig. 6.) Stop pins 122 engage the bars 111 to limit the clockwise movement of the plate.

The mechanism for actuating or moving the plate 101 in the present embodiment includes a connecting rod or link 125 and suitable transmission devices for reciprocating the link 125. The link 125 is hingedly connected to an eccentric collar or ring 126 through a pin 127 and yieldingly connected to the bracket 102 through the spacer 105. (Figs. 6 and 7.)

Annular collars 128 are formed on the spacer 105 for aligning the link 125. The spacer 105 is arranged in a slot 129 in the link 125 and is urged to the left end of the slot by means of tension springs 130 and 131 engaging the spacer 105 and the pin 127. At the opposite end, the slot 129 is offset to provide a stop shoulder 132, and an end of the link 125 is extended to provide a handle 133.

In order to insure operation of the plate 101 in timed relation to the rotary movement of the hats or of the shaft 67, I prefer to obtain power for operating the plate directly from the shaft 67 and to accomplish this I provide a clutch member 140 arranged for sliding movement on the shaft 67 and extending into a bearing hub 141 of the bracket 69. This clutch member is suitably slotted to receive a key 142 which is mounted in the shaft 67 and engages a companion clutch member 143 through ratchet teeth 144 or the like. The companion clutch member 143 also

provides a spur gear pinion 145 which meshes with a gear 146 carrying a pinion 147 meshing with a gear 148 carrying a pinion 149 and meshing with a gear 150 to which an eccentric 151 is secured by means of a rivet 152 or the like. The gear 146 carrying the pinion 147 and the gear 150 carrying the eccentric 151 are rotatably mounted on a shoulder stud or stub shaft 153 secured to the bracket 69 adjacent the shaft 67 by means of a nut 154. An end support is provided for the stub shaft 153 by a tie link 155 engaging the shafts 153 and 67 as indicated, (Fig. 6). A guard plate 156 is or may be provided for retaining the eccentric ring 126. A collar 157 suitably pinned to the shaft cooperating with suitable spacers and a flange 158 formed on the clutch member 143 holds the gear 148 with the pinion 149 and the clutch member 143 in axial alignment on the shaft 67.

The motor 16 is or may be suitably secured to a plate 181 which is suitably secured to the frame 11 and may be controlled by a suitable switch 182.

A hat to be cleaned is placed on the surface provided by the bottom of the receptacle 55, cleaning liquid from the well 58 is applied to the hat and brushed in, the excess liquid being drained off through the opening 56. After cleaning the hat is placed on the stretcher 90 or a suitable holder and mounted on the spindle 32. The spindle 32 is then assembled to the shaft 25 with the latch pin 93 engaging the spindle 32, with the motor 16 running the operating or control handle 64 is pulled out or to the left, (Fig. 1) bringing the friction wheel 61 into engagement with the friction surface 35 of the disc or pan 34 thus starting rotation of the shaft 25 and hat. As the handle 64 is moved farther to the left the rotary speed of the shaft 25 increases and as the wheel 61 moves under the pan 34 the spring 39 acting against the pan increases the frictional engagement in proportion to the increased driving strain and the rotary speed of the shaft 25 may be brought up to and beyond motor speed, thus effecting a mechanical elimination of cleaning liquid from the hat by centrifugal force. When the handle 64 is returned to normal position or the position shown, (Fig. 1) the drive is disconnected and the hat may be removed for pressing or ironing.

To accomplish this the hat is first placed on a crown block which is assembled to the spindle 72. The ironing mechanism is unlatched by engaging the handle 133 and raising the link 125 to release the spacer 105 and the plate 101 is manipulated to engage the hat just above the brim by means of the handle 113. An operating lever 161 pivotally mounted on a bracket 162 on the top 18 and having a bifurcated end 163 engaging in an annular groove 164 in the clutch

member 140 is then actuated to connect the clutch members 140 and 143 through their teeth 144 and through the gears 145, 146, 147, 148, 149 and 150 and the eccentric 151 the link 125 is slowly reciprocated yieldingly moving the bracket 102, the plate 101 and the associated parts toward the axis of the shaft 67 and to the position shown in dotted lines, (Fig. 6). In moving to the dotted position the plate 101 rolls about the hat from a substantially vertical to a substantially horizontal position and returns in one cycle of operation or one rotation of the eccentric 151, thus ironing the entire surface of the hat while it is rotated by the spindle 13. This operation may be repeated several times upon occasion. After ironing the crown the bracket 102 is again latched in retracted or normal position by the link 125 if the bracket 102 is manually moved slightly beyond its normal stroke. It will be noted that the yielding connection between the link 125 and the bracket 102 permits the entire ironing plate carrying apparatus to oscillate in accordance with variations in the diameter of the hat blocks and to assist the springs 119 a suitable fluid dash pot 190 is or may be provided having a plunger 191 pivotally secured to the ironing plate 101 and a fluid chamber or cylinder 192 similarly secured to the spacer 104, the dash pot being adapted to resist sudden retracting movement of the plate 101.

For ironing the hat brim the support or block 96 which may be of any suitable type is arranged on the shaft 67 and an extension tool or brim curling tool 170 which is preferably arranged to interlockingly engage the plate 101 is assembled thereto. The plate is then brought into contact with the work as shown, (Fig. 9) and the ironing operation repeated as for the crown to iron and curl the brim.

The tool 170 may be provided with a pair of keys or ribs 171 for engaging in keyways 172 formed in the plate 101 or may be dovetailed or otherwise connected thereto and is provided with an ironing point or lip 173 and a suitable handle 174. This tool is heated indirectly by the plate 101. The plate 101 may be heated in any suitable manner and in the present embodiment I have indicated an electrical conductor 175 and connector 176 through which current may be supplied to an inclosed electric heating element.

It is thought that the invention and many of its attendant advantages will be understood from the foregoing description, and it will be apparent that various changes may be made in the form, construction, and arrangement of the parts without departing from the spirit and scope of the invention, or sacrificing all of its material advantages, the form herein-before described being merely a preferred embodiment thereof.

I claim:

1. Mechanism for ironing hats and the like comprising, a hat block, a spindle for supporting said block, means for rotating the spindle, an ironing plate arranged for movement about the hat block, a pivoted carrier for said ironing plate, transmission devices associated with said spindle, and a reciprocating link yieldingly connecting said carrier and said transmission devices, said link being longitudinally yieldable and constructed and arranged to provide a latch for holding the ironing plate in an inoperative position. 70

2. In a device of the character described the combination with, a hat block, a rotatable spindle for supporting the block, and an ironing plate adapted for movement about said block to effect ironing, of means for controlling the ironing plate including, a vertically arranged pivoted bracket, a laterally extending link hingedly connected with said bracket and similarly connected with said plate adjacent an edge thereof, said plate and said link having a folding action as an incident to movement of the plate toward the axis of said rotatable spindle, spring means for resisting the folding action of said link and said ironing plate, and means for yieldingly actuating said link and said ironing plate through said vertically arranged bracket. 80

3. In an ironing device for hats and the like the combination with a hat crown iron of, a detachable extension iron for operating on the hat brim. 100

4. In an ironing device for hats and the like the combination with a hat crown iron of a brim curling iron interlockingly connected with said crown iron and heated thereby. 105

5. In a device of the character described the combination with, a hat block, a rotatable spindle for supporting the block, and an ironing plate adapted for movement about said block to effect ironing, of means for controlling the ironing plate including, a pivoted bracket, a link connecting said bracket and said plate, means associated therewith whereby said plate is yieldingly reciprocated toward and away from the axis of said spindle and simultaneously rotated about an axis extending through said link, and a dash pot device connecting said ironing plate and said pivoted bracket for controlling said plate. 110

6. In a hat finishing machine the combination with an ironing device and a carrier frame arranged to yieldingly support the ironing device for ironing operations and to direct movement thereof, of mechanical means having a longitudinally yielding driving connection with said carrier frame whereby said ironing device is moved to execute a predetermined cycle of operation subject to dimensional variations of hats. 125

MORRIS A. WEITZMAN. 130
